[57] **CLAIM**

The ornamental design for a handle for kitchen tools and gadgets, as shown and described

DESCRIPTION

FIG. 1 is a perspective view of a handle for kitchen tools and gadgets, showing our new design;

FIG. 2 is a top plan view thereof;

FIG. 3 is a side elevational view of one side thereof;

FIG. 4 is a bottom plan view thereof;

FIG. 5 is a side elevational view of the other side thereof;

FIG. 6 is a rear elevational view thereof; and,

FIG. 7 is a front elevational view thereof.

The broken line showings of a turner in FIGS. 1-7 are for illustrative purposes only and form no part of the claimed design.

The characteristic feature of the design resides in the black body of the handle provided with a metal cover on the top and bottom portions thereof with black resilient finger grips extending through both top and bottom metal covers of the handle.
